UNITED STATES PATENT OFFICE.

GEORGE J. HOOD, OF LAWRENCE, KANSAS.

DRAWING INSTRUMENT.

Application filed January 30, 1919. Serial No. 274,057.

To all whom it may concern:

Be it known that I, GEORGE J. Hood, a citizen of the United States of America, residing at Lawrence, in the county of Douglas and State of Kansas, have invented a certain new and useful Drawing Instrument, of which the following is a specification.

My invention relates to a drafting instrument and more particularly to a combination drafting compass and pen adapted to make circles in lead or in ink or to make straight-line ink drawings.

One object of my invention is to provide a compact, simple, inexpensive and easily manufactured pocket drafting instrument for use by amateur as well as professional draftsmen, which will take the place of an expensive and elaborate set of drafting instruments, each of which is specially adapted for a given purpose, and generally to provide a set of interchangeable parts which has a multiple of functions and uses depending upon the combination and arrangement of parts selected.

A further object of my invention is to provide a compass of variable radius which has no hinged joints capable of wearing loose, which has interchangeable drawing pen and pencil parts adapted to be held always in parallel relation to a fixed needle which defines the center of a circle, which has a beam rigidly mounted on the needle and an extension arm therefor adapted either for drawing circles of very large radius or for use separately as a drafting pen holder, and which has a carrier for the marking points, capable of being adjusted quickly and accurately in accordance with a scale marked thereon to any given radius, and resiliently held in any desired position without the use of clamping screws which are liable to be stripped of their threads.

With these and other objects in view, as will be apparent from the following disclosure, my invention resides in the combination of parts illustrated in the drawings and set forth in the specification, and the scope thereof is determined from the nature of the claims appended hereto.

I attain these objects by the mechanism illustrated in the accompanying drawing, in which Figure 1 is a front view and Figure 2 is an end view of the instrument as assembled for drawing circles in pencil; Figure 3 is the front view, Figure 4 the top view, and Figure 5 the end view of a slide for

holding the pen when drawing circles in ink; Figure 6 is a front view and Figure 7 a side view of the pen that is used for inking circles and lines; Figure 8 is a front view and Figure 9 an end view of a handle for holding the pen when drawing lines in ink and for use as an extension beam; Figure 10 is the front view of a pointed post.

In the embodiment of my invention illustrated in the drawings, the drafting set comprises essentially a compass post 1 having a beam 2 rigidly attached to the post above its lower end and at right angles thereto. The post 1 is provided at its lower end with a pointed needle 7 inserted therein as illustrated in Fig. 1, or formed on the body of the post 1 as shown at 28 in Fig. 10. The beam 2 is preferably located intermediate the ends of the post so that the upper portion of the post may be grasped by the fingers and rotated, and for convenience in operation of the instrument this head portion 25 may be knurled as illustrated.

In order to support a marking pencil rigidly and yet adjustably on this beam 2, I provide a carrier or slide 3 which is adapted to resiliently clamp against said beam with sufficient force to hold it firmly in position and yet permit of ready adjustment when grasped by the operator. This slide is made of considerable length as illustrated in Fig. 1, to prevent undesired lateral movements and to provide sufficient frictional engagement between it and the beam. I furthermore mount the drawing implement adjacent one end of the slide and provide means on the beam and slide which permit the slide to be mounted with either end adjacent the post so that either large or small circles may be drawn. To attain this interchangeability and provide for a resilient clamping engagement between the slide and beam, the latter may be formed, as illustrated in Figs. 1 and 2, of a strip of thin metal, having its opposite sides symmetrical, and the slide made to fit the same. The slide or carrier for the marking lead comprises members adapted to engage the sides of the metal strip 2 and to clamp resiliently but firmly thereagainst, irrespective of its position. One simple construction for producing this clamping action is embodied in a two part member having an arm adapted to engage one side of the beam 2 and resiliently connected to a second portion engaging the opposite side of the beam. As illustrated, a

100
105
110

single, long, narrow strip of resilient metal is bent up in a U-shaped form, and to prevent lateral movement of the clamping slide on the beam, there is provided means such as 5 a ribbed and grooved construction on the two parts which interfit and coact with each other. As shown in Figs. 1 and 2, a groove 9 is formed in the beam 2, preferably on each side thereof, in order that the slide 3 may 10 be reversible in position, and corresponding parts comprising the inwardly projecting ribs 10 are formed on the slide.

This carrier which travels lengthwise of the beam is adapted to hold a marking point 15 in parallel relation with the post 1. Referring to Figs. 1 and 2, the pencil marker comprises a projecting arm 4 securely and rigidly fixed to the U-shaped slide, which in the embodiment illustrated comprises a 20 single strip of metal folded upon itself to engage opposite sides of the U-shaped slide, and to form a long slot of substantially circular cross section (see part 32) which is adapted to hold a cylindrically shaped piece 25 of lead 5 slidably mounted therein. In order to permit insertion and adjustment of the lead, the two substantially flat portions 34 are slightly separated and at their lower ends 35 bent slightly outwardly to form 30 wedge shaped portions so that they may be drawn together by means of a U-shaped clamp 6 slidably mounted thereover, as shown in Figs. 1 and 2.

The pen for inking circles and lines is 35 shown in Figures 6 and 7. The body nib 13 of the pen is formed with the shanks 14 at the upper end. The hinged nib 15 of the pen is pivoted on the pin 16. A spring 17 holds the nibs normally together. The nib 10 15 may be swung away from nib 13 to permit of the pen being readily cleaned. The adjusting screw 19 regulates the width of line drawn by the pen.

Slide 8 shown in Figures 3, 4, and 5 is of 45 the same general cross-section as slide 3 and has grooves 12 to fit grooves 9 of beam 2. Slide 8 is formed with two sockets 11 of a size to fit shanks 14 of the pen. As illustrated, these sockets are located in projecting parts made by folding over portions 50 of the slide metal, lug 37 on one part being turned down over the other part to fasten the two halves together and strengthen the slide. The upwardly projecting shanks of 55 the pen being made of resilient material and of the shape of the sockets in the pen slide, fit with a resilient and clamping engagement in these sockets and hold the pen rigidly in position.

60 In order to extend the beam 2 and permit making circles of extremely large radius, I may provide an extension arm 20 illustrated in Figs. 8 and 9, which is of the same general cross section and shape as beam 2 65 and has two grooves 22 and 23 similar with

the grooves in the beam and running the full length of this extension arm. By placing one of the slide members on beam 2 in such a position as to project over its end, the extension arm may be inserted therein and it 70 provided in turn with the other slide member and its associated drafting point.

The drafting pen as herein illustrated is not provided with a sufficiently long handle for use by itself, hence I propose to utilize 75 the extension arm 20 for this purpose. To this end I provide another groove 27 in the arm adjacent one end and a clamping screw 21 having a head wide enough to extend over the groove 23 and the groove 27 opposite it. These grooves are made of such width as to permit the insertion of the projecting shanks 14 of the drafting pen therein. The drafting pen is clamped rigidly in position by turning the screw 21 down until 80 the head engages the sides of these shanks.

As illustrated in Fig. 1, the slot 4 of the pencil holder and the slots 11 of the pen holder may be so located relatively to the ends of the slides 3 and 8 or other suitable 90 index mark thereon that when the end of either slide or the mark registers with the desired mark of a scale 24 suitably located on the beam, then the distance between the needle point and the marking point will be 95 the same as the reading on the scale. Similarly, the parts may be so arranged and proportioned that when the slide is turned around for drawing larger circles, desired 100 measurements may be made.

The operation of my device is obvious from the above disclosure. In order to make a pencil mark of a small radius, the carrier 3 illustrated in Fig. 1 is located on the beam 105 with the pencil point on the end nearest the needle point 7. The clamp 6 is raised and a lead inserted in the groove in the U-shaped member formed by parts 4 and 34 and the clamp 6 is then drawn downwardly to hold the pencil point in place. In order to make 110 a circle of a radius substantially that of the length of the beam 2, the slide is reversed end for end. An ink mark may be made by positioning the pen carrier similarly on the beam. Circles of a very large 115 radius and straight line ink markings may also be made by utilizing the extension arm or handle 20 as above described.

By means of this construction, I provide 120 a drafting instrument of separate parts which are usable together and interchangeably for making pencil or ink circles of a large range of radii and for line drawings of any desired curves, these parts not being 125 complete separate instruments for different purposes but constituting necessary members of a single compact unit, whereby the necessity for carrying a large and varied set of drawing pens and pencils is entirely obviated.

Having thus described my invention, what I claim as new and desire to secure by Letters Patent is:—

1. A drafting compass comprising a post having a pointed end and a body portion adapted to be grasped by the hand for rotating the same, a beam attached medially to said post at right angles thereto, an extended slide resiliently clamping against the sides of said beam, but freely slideable and laterally immovable thereon, and a marking instrument on said slide.
2. A drafting compass comprising a pointed post having a hand hold at the end opposite the point, a beam having a scale thereon rigidly attached to a medial portion of the post, a reversible slide, having a scale line, which is resiliently and movably mounted on the beam, said slide and beam having cooperating members permitting the slide to be mounted on the beam with either end adjacent the post and yet preventing lateral movement thereof, and a marking implement adjustably mounted on the slide beneath the beam.
3. A drafting compass comprising a post having a pointed end and a body portion adapted to be grasped by the hand for rotating the same, a beam rigidly attached to said post at right angles thereto, a slide resiliently clamping against said beam, and having a member provided with a slot, a marking implement adapted to be removably mounted in said slot and means to hold said implement frictionally in position.
4. A drafting compass comprising a pointed post, a beam rigidly attached at right angles thereto, a slide resiliently clamped thereon, means, comprising an interfitting rib and groove on the slide and beam, to permit longitudinal and prevent lateral movement of the slide and a drawing implement removably mounted on the slide.
5. A drafting instrument comprising a pointed post, a ribbed beam rigidly attached at right angles thereto, a slide resiliently clamping against said beam and having a portion interfitting and coacting with the ribbed portion of said beam to prevent lateral movement but permit lengthwise movement of the slide on the beam and a marking implement carried by said slide.
6. A drafting compass having in combination a pointed post having a body portion adapted to be grasped by the hand for rotating the same, a beam rigidly attached at right angles to said post, a U-shaped slide comprising two extended arms resiliently engaging opposite sides of said beam which permit free longitudinal movement of the slide, a marking instrument and means on the slide to hold said instrument adjustably thereon.
7. A drafting compass comprising a pointed post, a beam rigidly fastened at right angles thereto, an adjustable slide hav-
- ing two extended arms, one resiliently engaging a large portion of one side of said beam and the other similarly engaging the opposite side, an interfitting rib and groove construction on said beam and slide to prevent lateral movement of the slide, a drawing implement and yielding means to hold the implement in adjustable position on said slide.
8. A drafting compass comprising a pointed post and a beam rigidly attached substantially at right angles thereto, an extension arm fashioned conjunctively with the beam for longitudinal alignment therewith, means for securing said arm and beam in alignment to lengthen the effective radius of the compass, and a drawing instrument mounted on said extended beam.
9. A drafting compass comprising a pointed post, a beam rigidly fastened at right angles thereto for carrying a drawing instrument, an extension arm of the same cross section as the beam, a slide having resilient members clamped over the ends of said beam and arm to fasten them together, a slide adjustably and resiliently clamped on said arm, and a marking instrument mounted thereon.
10. A drafting compass comprising a pointed post, a beam rigidly fastened at right angles thereto for carrying a drawing instrument, an extension beam of similar cross section, said beams being relatively fashioned for longitudinal alignment, a resilient clamp for securing said beams together, a slide fashioned for coactive functioning with said beams, when so joined, and for resiliently engaging the extended beam in a manner to permit longitudinal adjustment thereon and a drawing implement mounted on said slide.
11. A drafting compass comprising a pointed post, a beam rigidly fastened thereto, a slide adjustably mounted on the beam and having two slots therein and a drawing implement having projecting arms slidably and resiliently held in said slots.
12. A drafting instrument comprising a pointed post having a beam rigidly attached at right angles thereto, a V-shaped slide resiliently and movably engaging said beam, an extension arm adapted to be fastened to said beam by said slide, a second V-shaped slide adapted to be mounted on either the extension arm or the main beam, and a drawing point carried by said second slide.
13. A drafting compass, comprising a centering post, a beam attached to the post, a slide resiliently engaging the beam, an implement holding member attached to the slide which is fashioned to provide clamping members, a marking implement, and means applied to said clamping members to effect closure upon said implement.
14. In a drafting compass, a centering

post, a beam attached rigidly to said post, an implement support applied to the beam which is fashioned to provide resiliently active tension members adapted to permit the support to slide on the beam, a drawing implement and means on said support to effect closure upon said implement.

15. A drafting compass, comprising a centering post, a rigid beam extending laterally therefrom, a tool supporting member which is fashioned conjunctively with the beam to facilitate longitudinal alignment

therewith to extend the effective radius of the compass, adjustable means to fasten said member and beam in alignment, a slide on 15 said member and an implement holder attached to the slide.

In witness whereof I affix my signature this 27th day of January, 1919, in the presence of two witnesses.

GEORGE J. HOOD.

Certificate of Correction.

It is hereby certified that in Letters Patent No. 1,461,421, granted July 10, 1923, upon the application of George J. Hood, of Lawrence, Kansas, for an improvement in "Drawing Instruments," errors appear in the printed specification requiring correction as follows: Page 1, after line 64 insert the paragraph

Similar numerals refer to similar parts throughout the several views.:
page 2, line 58, for the misspelled word "socktes" read *sockets*; page 3, lines 114 and 118, claim 12, for *V*-shaped read *U*-shaped; and that the said Letters Patent should be read with these corrections therein that the same may conform to the record of the case in the Patent Office.

Signed and sealed this 14th day of August, A. D., 1923.

[SEAL.]

KARL FENNING,
Acting Commissioner of Patents.
